UNITED STATES PATENT OFFICE.

WILLIAM C. WINFIELD, OF WARREN, OHIO.

LIFT MECHANISM FOR TUBULAR LANTERNS.

SPECIFICATION forming part of Letters Patent No. 634,079, dated October 3, 1899.

Application filed January 26, 1899. Serial No. 703,453. (No model.)

To all whom it may concern:

Be it known that I, WILLIAM C. WINFIELD, a citizen of the United States, residing at Warren, in the county of Trumbull and State of Ohio, have invented certain new and useful Improvements in Lift Mechanism for Tubular Lanterns; and I do declare that the following is a full, clear, and exact description of the invention, which will enable others skilled in the art to which it appertains to make and use the same.

This invention has reference to lift mechanism for tubular lanterns; and the object of the invention is to provide means for conveniently raising the globe to effect lighting and to lower the globe again to its seat, all substantially as described and shown, and particularly pointed out in the claims.

In the accompanying drawings, Figure 1 is a front elevation of my improved lantern, showing the globe seated. Fig. 2 is a side elevation with parts broken away and showing the globe raised. Fig. 3 is a cross-section on line 2 2, Fig. 1, looking upward and in dotted lines showing the lift mechanism in the half-raised position.

A represents the usual tubes or tubular frame of the lantern, and B is the globe carried by the frame, consisting of the side wires C, bottom plate D, and canopy E. These latter parts are connected to be raised and lowered together, a spring-wire loop b confining the globe at its top, as usual.

G is a crank lifting-lever shaped substantially as seen in Fig. 1 and pivoted at about its middle in a suitable bearing on the side tube A. The inner elbow portion of this lever extends to about the edge of the plate D, where it is engaged in an ear on a sliding sleeve H on an arm J, fixed permanently and rigidly on the plate D and preferably at or about its central opening, as seen in Fig. 3, though of course it might be otherwise or elsewhere attached thereon without departing from the invention. This arm J has its horizontal sleeved portion 2 arranged outside the globe-bottom in the line of travel prac-

tically of the inner extremity of crank-lever G as it makes its curved sweep transversely back and forth in raising and lowering the globe, and the sleeve H affords both a sliding and a pivotal connection with said arm. This makes a very easy operating movement, as the sleeve readily accommodates itself to the different positions of the lifting-lever in its rotations.

L is a wire spring bent into a loop and secured at one end to the globe-plate D and at the other to the inner extremity of lever G or to the sleeve H and coöperating with the lever in raising and lowering the globe, as well as serving to help to hold the globe securely in both raised and lowered positions.

Thus when the crank-lever lifts the globe it no sooner reaches the horizontal or half-way position than the spring J begins to exert an upward or lifting pressure, and it alone will securely hold the globe up without other means for locking lever H. On the other hand, in lowering the globe after the half-way place is passed the spring exerts a downward pressure, and as the globe becomes seated it maintains a constant downward pull, thus keeping all the parts in their place.

The usual guides a on the tubes for the side wires C are employed, and the canopy is free to slide and rise on the central draft-tube a', as seen in Fig. 1.

What I claim is—

1. In a tubular lantern, the globe-carrying frame, an arm rigid with said frame and a sliding member on said arm, the tubes and a lever pivoted thereon and loosely connected with the said sliding member, whereby the globe is raised and lowered, substantially as described.

2. The globe-frame and an arm fixed on the bottom thereof, in combination with the tubes and the swinging lever, and a part sleeved on said arm and freely connected with said lever, substantially as described.

3. The tubular frame and the lifting-lever supported thereon, in combination with the vertically-movable globe-frame, an arm on

the said frame having a straight portion substantially in the path of said lever, and a sleeve on said straight portion pivotally connected with the said lever, substantially as described.

4. The tubular frame and the crank-lever thereon, in combination with the globe-frame and an arm fixed thereon, a sleeve on said arm pivotally connected with the said lever

and a spring operatively connected with said arm, substantially as described.

Witness my hand to the foregoing specification this 12th day of January, 1899.

WILLIAM C. WINFIELD.

Witnesses:

W. A. SPILL,

M. D. KEE.
